UNITED STATES PATENT OFFICE.

CLARENCE L. EATON, OF BINGHAMTON, NEW YORK, ASSIGNOR TO THE UNITED SHOE MACHINERY COMPANY, OF BOSTON, MASSACHUSETTS, A CORPORATION OF NEW JERSEY.

CHANNELING AND GROOVING MACHINE.

No. 885,232.

Specification of Letters Patent. Patented April 21, 1908.

Application filed August 1, 1902. Serial No. 117,855.

To all whom it may concern:

Be it known that I, CLARENCE L. EATON, a citizen of the United States, residing at Binghamton, in the county of Broome and State of New York, have invented certain new and useful Improvements in Channeling and Grooving Machines; and I do hereby declare the following to be a full, clear, and exact description of the invention, such as will enable others skilled in the art to which it appertains to make and use the same.

The present invention relates to machines used in the manufacture of boots and shoes, and more particularly to machines for preparing the outsoles of boots and shoes to be secured to the lasted upper, welt and insole of welted boots and shoes.

More particularly the invention relates to certain improvements upon the machine disclosed in Letters Patent of the United States granted to United Shoe Machinery Co. on the 8th day of October, 1901, No. 684,359, upon an application filed by me.

The machine of the aforementioned patent comprises certain improvements in rough rounding and channeling machines, such as disclosed in Letters Patent of the United States No. 600,883, issued on the 22nd day of March, 1898 to W. C. Meyer and Z. T. French, and has for its object the production of a machine for rough rounding and channeling the outsoles of boots and shoes, and particularly to certain improvements in the channeling mechanism of such machines whereby the operator may, at will, throw out of operation the channeling knife, without affecting the operation of the rounding knife, so that certain portions of the shoe sole may be rounded and channelled, and certain portions thereof may be rounded without channeling, whereby the stitches which unite the outsole to the welt are placed upon the tread surface of the sole, which method of uniting the outsole to the welt is known in shop parlance as "stitching aloft".

The object of the present invention is to provide a channeling machine, and particularly a channeling machine embodying rough rounding mechanism, generally known in the art as rough rounding and channeling machines, and provided with a channeling knife which may be thrown out of operation substantially as disclosed in Letters Patent of the United States No. 684,359, hereinbe-

fore referred to, with a grooving knife so combined and arranged with relation to the channeling knife, that when said channeling knife is in operation, the grooving knife is out of operation, and when the channeling knife is out of operation, the grooving knife is in operation, acting to form a groove in the tread surface of the outsole in such portions thereof in which it is desired to have the stitches show. Thus while producing all the effect, in so far as the appearance of the tread surface of the sole is concerned, of those shoes wherein the outsole is attached by "stitching aloft", at the same time producing a shoe sole in which the visible stitches are to a certain extent protected from wear.

To the above ends the present invention consists of the devices and combinations of devices which will be hereinafter described and claimed.

The present invention is illustrated in the accompanying drawings, in which:

Figure 1 shows a front elevation of the upper part of a rough rounding and channeling machine embodying my improved grooving and channeling mechanism. Fig. 2 shows a top plan view of the block carrying the channeling and grooving knives, showing in full lines the position of the knife holder when the channeling knife is in operation, and the grooving knife out of operation, and in dotted lines the position of the said knife holder when the channeling knife is out of operation, and the grooving knife is in operation. Fig. 3 shows a bottom plan view of the vibrating block and its immediate mechanism, shown in Fig. 2. Fig. 4 shows in side elevation and partial sectional view the parts shown in Fig. 2. Fig. 5 shows a side elevation of the parts shown in Fig. 2. Fig. 6 shows the movable part of the clamp of the channeling knife. Fig. 7 shows a sectional view taken on the line x-x, in Fig. 4, looking in the direction of the arrow in said figure. Fig. 8 shows a plan view of a rounded and channelled outsole, and Fig. 9 shows a plan view of a rounded outsole having a channelled shank portion and a grooved ball and fore part.

Similar reference characters will be employed throughout the specification and drawings to designate corresponding parts.

As illustrated in the accompanying drawings I have shown the invention as incorpo-

rated in a machine for rough rounding and channeling outsoles attached to the lasted upper, that is to say, a machine which prepares the outsole for the action of the stitch forming mechanism used in uniting the outsole to the lasted upper and insole while said outsole is temporarily secured to the lasted upper and insole by cement after said outsole has been "laid", that is to say, subjected to pressure in a sole laying machine, which causes said outsole to approximately assume the contour of the bottom or tread surface of the last; this method of rounding and channeling outsoles being now almost universally employed in the manufacture of the better grades of shoes, for the reason that the contour of the outsole is controlled by the sides of the last or the position of the in-seam, and thus more accurately conforms thereto than those soles which are rounded and channeled before being "laid".

As hereinbefore stated, the machine as illustrated is substantially the same as that disclosed in the patents hereinbefore mentioned, and comprises a frame A, a cutting plate B which bears against the upper face of the welt and against the rear face of which the rounding knife acts in making its cut, a crease gage C, a last gage D, a laterally reciprocating block or carrier E for the channeling and rounding knives, a channeling knife F, and the loosely turning sole rest G against which the tread surface of the outsole is held during the operation of the machine.

As in the machine of the Patent No. 684,359, the channeling knife F is mounted in a knife carrier supported by the upper end of a spindle a arranged to turn in a bearing b formed in a casting c, held by means of a bolt c¹ to the lower end of the reciprocating block E. The upper end of the spindle a is provided with a guard plate a¹ preferably formed integrally with said spindle, which rests upon and is arranged to move over the upper end 45 of the block E, and preferably provided upon its under face with a curved groove a², which is engaged by a curved rib a³ formed at the upper end of the block E.

The form of the guard plate a¹ is clearly shown in Fig. 2 of the drawing, and as shown therein, it is cut out forming a shoulder a⁴, against which one side of the channeling knife F is held by the knife clamp d, shown in perspective in Fig. 6 of the drawing. The knife clamp d is provided with an under cut shoulder d¹, which engages the opposite side of the shank of the channeling knife and it is caused to clamp said knife, and held in position on the plate a¹ by means of a set screw d² which passes through a hole in the upper end of the spindle a and engages a threaded aperture in the knife carrier d. The channeling knife and its method of attachment as illustrated herein, do not differ in any essential particular from the patents herein-

beforementioned. Like Patent No. 684,359, the spindle a, its guard a¹ and the channeling knife F are arranged to turn about the axis of said spindle a, so as to throw said knife into and out of operative position, and I have arranged to support a grooving knife upon said spindle a at substantially an angle of 15 degrees with relation to the channeling knife, so that when said channeling knife shall be thrown out of operation, the grooving knife may be caused to occupy the position held by the channeling knife, and to continue the operation upon the shoe sole begun by the channeling knife, thus forming a groove extending from the channel, as clearly shown in Fig. 9 of the drawing.

The grooving knife may be of any of the usual forms of such knives, but as shown in the drawing comprises a shank e having at its outer end a circular cutting portion e¹, and it is held to the spindle which supports the channeling knife by means of a set screw e² and washer e³, the said screw engaging a threaded aperture e⁴ in the head of the set set screw d², which holds the channeling knife in position.

As shown in Figs. 2 and 3 the channeling and grooving knives are so positioned with relation to each other, that a slight turning of the spindle a will remove the channeling knife from operative position and place the grooving knife in operative position, and vice versa.

Like the device of Patent No. 684,359, I provide suitable means for maintaining the spindle carrying the channeling and grooving knives in the extreme of its two positions and preferably employ a spring whereby to cause said spindle to be quickly turned to retract the channeling knife and project the grooving knife, and have provided a simple latch to maintain said spindle and grooving knife in such a position as to cause the channeling knife to act on the sole. The mechanism is somewhat simpler than that of the patent last above mentioned, and will now be described.

To the lower end of the spindle a there is fastened by means of a key f and a set screw f¹ a laterally extending arm f² which arm is engaged by one end f³ of a spring coiled about a stud f⁴, the opposite end f⁵ of said spring engaging a latch f⁶ held to turn about the stud f⁴. It will be seen that the end f³ of the spring has a tendency to throw the arm f² into the dotted line position shown in Fig. 2, thus bringing the grooving knife into its operative position, and that the end f⁵ of said spring has a tendency to cause the notched end of the latch f⁶, which fits in a cut away groove f⁷ of the arm f², to engage the outer face of said arm and restrain it from movement under the influence of the end f³ of said spring. As shown in Fig. 3, the latch f⁶ has released the arm f² and the

end f^3 of the spring has thrown the spindle a into position to throw the grooving knife e^1 into operative position.

If the operator should desire to bring the channeling knife F into position, pressure upon the arm f^2 in the direction indicated by the arrow in Fig. 3 will turn the spindle a , and when said arm f^2 has been moved sufficiently to permit the notched end of the latch f^6 to engage the outer face of the arm f^2 , the end f^5 of the spring will cause said latch to engage the arm f^2 and hold the spindle a in the position shown in full lines in Fig. 2.

15 Inasmuch as the change from a channeling to a grooving operation must be quickly made, I have provided the latch f^6 with a downwardly extending finger piece f^8 , by means of which it may be quickly operated 20 to cause it to release the arm f^2 and permit the spring to turn the spindle a , as hereinbefore described.

Fig. 8 shows an outer sole rounded and channelled as it may be done in a machine 25 equipped with the present invention when embodied in a rounding and channeling machine.

Fig. 9 shows an outsole provided with a channel along the shank portion and a groove 30 g along the ball and forepart, as produced by the present machine.

It will, of course be obvious that if so desired, the outsole may be formed with a groove extending entirely around its tread 35 surface, omitting the channel at all portions thereof.

It is thought that the operation of the present invention has been sufficiently described in connection with the foregoing description of the form and arrangement of the machine illustrated in the drawing, and that a further description of its operation will be deemed unnecessary.

Having described my invention, I claim as 45 new and desire to protect by Letters Patent of the United States.

1. A rough rounding and channeling machine, having, in combination, a channeling knife, a grooving knife, a single support for 50 both knives, and means for moving the support to throw one knife into, and the other

knife out of, operation during the continued operation of the machine, said knives being so located on said support with relation to each other that the operation of one knife 55 commences immediately upon the interruption of the operation of the other knife, substantially as described.

2. A rough rounding and channeling machine, having, in combination, a channeling 60 knife, a grooving knife, a single rotatable support for both knives, and means for rotating the support to throw one knife into, and the other out of, operation during the continued operation of the machine, said 65 knives being so located on said support with relation to each other that the operation of one knife commences immediately upon the interruption of the operation of the other knife, substantially as described. 70

3. A rough rounding and channeling machine, having, in combination, a channeling knife, a grooving knife, a rotatable sole support, and a rotatable spindle for carrying 75 said sole support, said knives being supported on said spindle and adapted to be thrown, the one, into, and the other, out of, operation, by turning said spindle, substantially as described.

4. A rough rounding and channeling machine having, in combination, a knife support having provision for a limited oscillation about a center close to the surface of the work, a channeling knife and a rounding knife mounted upon the knife support in 85 close proximity to each other, and means for swinging the knife carrier in one direction to throw the channeling knife into operation and in the opposite direction to throw the grooving knife into operation during the continued 90 operation of the machine, the operation of one knife commencing immediately upon the interruption of the operation of the other knife owing to the relative positions of the knives, substantially as described. 95

In testimony whereof I affix my signature, in presence of two witnesses.

CLARENCE L. EATON.
